UNITED STATES PATENT OFFICE.

WALTER J. COOPER, OF CLEVELAND, OHIO, ASSIGNOR TO EDWARD UMBSTAETTER,
OF CLEVELAND, OHIO.

HYDRAULIC LIFTING JACK.

Application filed March 14, 1924. Serial No. 699,176.

To all whom it may concern:

Be it known that WALTER J. COOPER, a citizen of the United States, residing at Cleveland, in the county of Cuyahoga and State 5 of Ohio, has invented certain new and useful Improvements in a Hydraulic Lifting Jack, of which the following is a specification.

My invention relates to a hydraulic lifting jack, and my object in general is to provide a portable jack in which an operating plunger is adapted to be quickly and conveniently placed in different angular operating positions relatively to a vertical lifting 10 member, thereby permitting the jack to be placed in crowded quarters beneath the object and to be operated from different angles where most accessible and convenient. The jack is especially useful as a vehicle jack, 15 as it may be used beneath the body or axle relatively close to the wheels or other obstructions and still readily accessible for operation from many different angles, and very heavy loads may be easily lifted with a relatively small jack. Other objects are featured 20 in the details of construction as will hereinafter be pointed out and described.

In the accompanying drawings, Fig. 1 is 25 a side elevation of the jack, and Fig. 2 is a side view, partly in section, showing the operating plunger and its cylinder in a slightly inclined position in full lines and in still another inclined position in dotted lines. Fig. 3 is a horizontal section of the 30 jack on line 3-3 of Fig. 1. Fig. 4 is a side elevation of the lifting plunger. Fig. 5 is a perspective view of the stationary screw for the operating ram or plunger. Fig. 6 is a top view of the swivel member for the 35 operating plunger, showing the locking pin and outlet port in the bottom thereof. Fig. 7 is a side view of the portion of a modified form of the invention.

The jack comprises a flat base 2 adapted 40 to support a round hollow cylinder 3 in an upright position and in open communication with a central hollow boss 4 upon said base. Lateral bosses 5-5' extend from opposite sides of central boss 4 and these bosses 45 are bored to receive the round hollow stem 6 of a swivel member 7 which has an annular flanged enlargement 8 adapted to support a hollow cylinder 9 within which an assembly 50 of screw plunger parts may be removably and operably confined. A screw plug

10 closes the outer end of one of the bosses 5 and a ring nut or packing gland 11 is sleeved upon swivel stem 6 and screw-engaged with the other boss 5'. Stem 6 has a longitudinal passage 12 with a round port 13 opening into hollow boss 4 and the bottom end of stationary cylinder 3, and a round duct 14 also extends from passage 12 through enlargement 8 into the base end of the movable cylinder 9. This open passageway between the 60 two cylinders is constantly maintained in all the swiveled positions assumed by movable cylinder 9 and its swivel stem 6.

Stationary cylinder 3 contains a reciprocable plunger 15 which is free to slide there-in within limits as determined by a shoulder or enlargement 16 at its upper end and by a metal disk 17 screwed or bolted to its lower end. Plunger 15 and its disk 17 is of smaller diameter than the internal diameter of hollow cylinder 3, and a screw collar 18 may be used to secure the plunger in place and provide a bearing for its movement through the upper end of cylinder 3. A packing gland or nut 19 may also be used in connection with collar 18 to seal the joint around the plunger. The upper end of plunger 3 may be provided with a thrust or rest member 20 of any suitable kind or construction to carry the load.

Cylinder 9, which is movable in an arc at 65 the side of stationary cylinder 3, contains a stationary screw member 21 and a rotatable screw member 22. Member 21 comprises a hollow stem provided with external screw-threads, and member 22 is a tube with internal screw threads engaged with said screw stem, the latter having an enlargement or base part 23 adapted to seat snugly within the flanged and recessed enlargement 8 of swivel member 7. A round pin 24 fixed 70 within the recess is adapted to enter a round hole 25 in base port 23 to prevent the screw stem or member 22 from turning. When so fixed a notch 26 in base part 23 registers with duct 14 in swivel member 7 75 and the oil or liquid within the jack may be transferred from one cylinder to the other by the movement of the plungers. Thus the rotatable screw member 22 may be rotated within cylinder 9 by means of a crank or 80 operating shaft applied to the square or angular projection 27 at its outer exposed end, and in so doing tubular member 22 travels longitudinally of the screw stem in either direction dependent upon the direc- 85

tion of rotation given. A screw collar 28 supplemented by a closely fitting sealing ring or nut 29 provides a bearing and closure at the outer end of cylinder 9 for the tubular screw member or operating plunger 22. The chamber within tubular member 22 is open to the central bore in the stationary screw member 21, and a lateral opening 30 at the lower end of the hollow screw stem is open 10 to the chamber within cylinder 9 and which chamber is in turn in constant open communication with the transfer passage in the swivel member by way of notch 26 and duct 14.

15 In operating the jack, it may be placed in an upright position beneath an axle of a vehicle closely adjacent a wheel, and the movable cylinder turned to the most desirable angle which will give access to the 20 operating plunger and facilitate operations. Screw plunger 22 may then be rotated to displace the oil, grease or liquid within cylinder 9 and to transfer it to stationary cylinder 3 where it will act to raise lift member 25 or plunger 15 and the load. A reversal of rotation of screw plunger 22 will permit a reverse flow of the fluid within the cylinders and permit the lift plunger to descend. The 30 swiveled cylinder may be turned to an upright position or to the left or right to a horizontal position. Stationary screw member 21 is clamped upon swivel member 7 by means of cylinder 9, and by unscrewing said cylinder both the stationary and movable 35 screw members 21 and 22 may be bodily removed and separated. In filling the cylinder with oil or other fluid it is necessary that no air be pocketed within the cylinders, and therefore, I provide plunger 22 with a small orifice and valve seat 32 at its outer end for the escape of air and also provide a screw 40 33 with a pointed end to engage the seat and

close this orifice when the device is filled and in use.

In Fig. 7, I show the same swivel member 45 7 of the jack connected with the base at one side of stationary cylinder 3 and with a communicating passage at the bottom thereof. The device may be made in this way to permit the use of a longer chamber or a 50 more extended travel of a plunger in either cylinder, applying the comparison to the two structures shown herein.

I claim as my invention or discovery:

1. A hydraulic lift jack, comprising a pair 55 of cylinders having a swiveled coupling provided with a passage for the transfer of a fluid from one cylinder to the other, operating and lift plungers in said cylinders, the operating plunger being a rotatable hollow 60 screwthreaded member, a stationary hollow screw member extending into said operating plunger having a disk-shaped base and formed with an opening near said base and the cylinder for the operating plunger being 65 screwed in clamping engagement with said base to hold said screw member in a stationary and removable position upon said coupling.

2. A hydraulic lift jack, comprising a 70 pair of cylinders in swiveled connection and in open communication for the transfer of a fluid from one to the other cylinder and plungers in the cylinders; the operating plunger in one cylinder comprising a hollow 75 screw member, and formed with a slotted disk-shaped base having an opening, and a seat for said base having a pin and an opening registering with the opening and slot, respectively, in said base. 80

In testimony whereof I affix my name hereto.

WALTER J. COOPER.
